(57) **CLAIM**

The ornamental design for a drawer pull, as shown and described.

DESCRIPTION

FIG. 1 is a perspective view of a drawer pull showing my new design;

FIG. 2 is another perspective view thereof;

FIG. 3 is a left side elevational view thereof, with the right side elevational view and top and bottom views being identical thereof;

FIG. 4 is a front elevational view thereof; and,

FIG. 5 is a rear elevational view thereof.

The broken lines in FIG. 2 are for illustrative purposes only and form no part of the claimed drawer pull.
